CLAIM

The ornamental design for a cutting board base with trash bag holder, as shown and described.

DESCRIPTION

FIG. 1 is a front perspective view of a cutting board base with trash bag holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof, shown in a position of use with an exemplary trash bag.

The broken lines are shown for the purpose of illustrating exemplary environmental subject matter of a trash bag, and form no part of the claimed design.

1 Claim, 9 Drawing Sheets
